WELL TOOL RETRIEVER

Edward Bradberry Miller and Grover Cleveland
Stewart, Hobbs, N. Mex.

Application April 30, 1951, Serial No. 223,712

2 Claims. (Cl. 294—86)

1

This invention relates to a well tool retriever. In well-drilling operations it frequently happens during the drilling operation that the drill bit or other tool either breaks or becomes separated from the drill stem. Further drilling must necessarily be suspended until the broken or disconnected tool can be removed as otherwise the broken or disconnected tool being highly tempered and formed of tool steel will damage any new tool.

It is, therefore, an object of this invention to provide a retrieving means for attachment to a drill stem or valve tool, which is designed for use under hydrostatic pressure for gripping the broken tool so as to permit removal of the tool with the drill rod.

Another object of this invention is to provide a tool retrieving device wherein the article to be retrieved is forced into the tool under fluid pressure, and the article gripped by means of radially disposed spring-pressed gripping fingers.

A further object of this invention is to provide a tool retrieving device which is relatively positive in action and will usually retrieve the tool in one operation.

With the above and other objects in view, my invention consists in the arrangement, combination and details of construction disclosed in the drawings and specification, and then more particularly pointed out in the appended claims:

In the drawings:

Figure 1 is a detailed side elevation of well tool retriever constructed to an embodiment of this invention.

Figure 2 is a fragmentary sectional view taken on line 2—2 of Figure 1.

Figure 3 is a fragmentary sectional view taken on the line 3—3 of Figure 1.

Figure 4 is a sectional view taken on the line 4—4 of Figure 3.

Figure 5 is a sectional view taken on the line 5—5 of Figure 3.

Figure 6 is a fragmentary sectional view taken on the line 6—6 of Figure 4.

Figure 7 is a fragmentary side elevation of the locking connection between the outer casing and the inner valve operator.

Figure 8 is a fragmentary sectional view taken on the line 8—8 of Figure 7.

Referring to the drawings, the numeral 10 designates generally an outer casing formed of tubular upper and lower sections 11 and 12. The casing 10 is adapted to be lowered into a well opening or well casing and may be formed at the lower end thereof in the shape of a well tool or bit. The lower casing member 12 has disposed therein a lower cylindrical collar 14 which is seated on an annular shoulder 13 formed on the interior of the casing section 12. The collar 14 as shown in Figure 5 has pivotally mounted on inner side thereof a plurality of radially disposed

2

article gripping fingers 16 which are provided on their outer ends with a pair of ears 17 extending into vertical slits or recesses 18 formed in the inner side of collar 14.

5 The fingers 16 are adapted to be normally in a horizontal position and are constantly urged to a normal operative position by means of springs 19. As shown in Figure 5 there are two series of article gripping fingers; the second series of 10 gripping fingers designated as 20 are substantially shorter in length than the first series of gripping fingers 16.

A second cylindrical collar 21 is disposed in the lower casing member 12 above the lower collar 14 and has pivotally mounted on the inner side thereof, as shown in Figure 4, a plurality of radially disposed article gripping fingers 22. The article gripping fingers 22 are constantly urged downward to a horizontally operative position by means of springs 23. The fingers 22 when disposed in a horizontal position are adapted to engage on a shoulder 24 formed on the inner side of casing member 12. The gripping fingers 16 and 20 as shown in Figure 5 are formed with blunt 25 inner ends 25 and 26 respectively, whereas the gripping fingers 22 are formed with pointed inner ends 27.

A second series of upper gripping fingers 28 are 30 pivotally carried by the upper cylinder 21 being positioned between the outer portions of fingers 22. The gripping fingers 28 are of triangular configuration, being pointed at their inner ends, and are adapted to cooperate with fingers 22 in gripping an article particularly where the article 35 may be formed of offset elements which may not readily be gripped by the longer gripping finger 22.

The casing 11 has slidably disposed therein above the upper collar 21 a spring-pressed valve 29 normally urged to a closing position against 40 a valve seat 30 formed on the lower end of a collar 31. The valve member 29 is constantly urged upwardly to closed position by means of spring 32. The valve member 29 is formed with a series of ports 33 which are normally disposed out of 45 registry with a series of ports 34 which are formed in the collar 31. A second valve member 35 is slidably disposed in a valve guide or collar 36 carried by the casing member 11 and is constantly urged upwardly to a closed position against a seat 37 by means of a spring 38. A spring 39 is disposed in a bore 40 formed in the lower valve member 29 and bears against a projecting stem 41 carried by the valve plug or head 42.

The lower stem 41 is formed with one or more 50 ports 43 which are normally disposed in communication with a chamber 44 which is formed below the guide or collar 36. The bore 40 in valve member 29 communicates with a smaller bore 35 which extends through the lower end of 55 valve member 29. When the valve head 44 is moved downwardly as will be hereinafter de-

scribed, valve member 44 will engage the upper end of valve member 29 so as to cut off communication of bore 40 with chamber 44 through ports 43.

The valve member 35 is formed with a plurality of vertically spaced apart ports 46, the lower one of which communicates with an annular chamber 47 formed in collar 36 above valve seat 31. Collar 36 is also formed with a plurality of upwardly extended ports 48 which communicate chamber 47 with an upper chamber 49.

A tubular valve operator 50 is slidably and rotatably carried by upper casing member 11 and, upon downward movement of operator 50, the lower end of this member is adapted to bear against a cap or head 51 which is carried by valve member 35 so that the latter member will be moved downwardly to an open position. The operator 50 is releasably locked against rotation and endwise movement relative to casing member 11 by means of a locking lug 52 which is secured to the operator 50 and projects through a keeper opening 53 which is formed in the casing member 11. The keeper opening 53 includes a horizontally extending locking portion 54 extending laterally to the left of opening 53 and also including a lower locking portion 55 which extends in the opposite direction from locking portion 54. The opening 53 includes a cam shaped edge 56 which merges with the upper edges of portions 54 and 55 and provides a means whereby the cam shaped end 57 of locking member 52 may move the operator 50 endwise to a valve opening position.

In the use and operation of this device, the operator 50 is connected to a pipe of suitable length so that the casing 10 may be extended to the bottom of the well. The casing is then subjected to a weight of from 1,000 to 1,500 pounds to assure the bottom of the casing or drill stem being positioned on the bottom of the well. The casing 10 is then lifted upwardly a short distance and rotated very slowly in a clockwise direction while simultaneously moving the casing down to the well bottom. The rotation of the casing 10 is then reversed while at the same time applying a weight of substantially 5,000 pounds or more to the drill stem so that the locking lug 52 will partially rotate with operator 50 so as to move lug 52 from upper locking keeper 54. When lug 52 engages cam surface 56, operator 50 will move endwise and downwardly so that the lower end of operator 50 will move valve members 51 and 29 downwardly to an open position. At this time mud or other liquid is inserted in the well casing about casing member 10 under pressure so that the disconnected tool which is now positioned in the lower end of casing member 12 will be forced upwardly either past the gripping fingers 16 or 22 or to a position whereby the tool will be engaged by the gripping fingers 16 and 22. Preferably the operation of rotation of casing 10 is performed at least twice in order to assure that the disconnected tool will be extended into the lower end of lower casing member 12 and will subsequently be forced upwardly by the mud or other fluid which is forced upwardly through the casing member 10.

A well tool retriever constructed according to the device hereinbefore described will provide a means whereby the disconnected or broken tool or bit may be pulled from the well casing in a single pulling operation.

What is claimed is:

1. A well tool retriever comprising a tubular casing, a cylindrical collar disposed in the lower

portion of said casing, radially disposed article gripping fingers carried by said collar and normally disposed in a horizontal position, a second collar above said first collar, radially disposed article gripping fingers carried by said second collar and normally disposed in a horizontal position, upwardly closing spring-pressed valve means in said casing above said second collar opening of said valves permitting fluid under pressure from the exterior of said casing to flow inwardly to force a tool to be retrieved upwardly into the interior of the casing to cause said tool to be moved into position to be engaged by said finger, a tubular valve operator slidably and rotatably disposed in said casing, said casing having a horizontally elongated opening therein formed with an upper locking portion and a lower locking portion extending oppositely from said upper locking position, said opening being formed with an inclined cam surface extending between said locking portions, and a combined locking lug and cam member fixed to said operator and projecting into said opening, rotation of said operator in a counterclockwise direction relative to said casing effecting simultaneous endwise downward movement of said operator to dispose said lug in said lower locking portion with said operator in a valve opening position said lug locking said valve operator and casing against endwise movement relative to each other in either valve opening or valve closing position.

2. A well tool retriever comprising a tubular casing, lower radially disposed spring-pressed article gripping fingers carried by said casing adjacent the lower end thereof, and normally disposed in a horizontal operative position, upper radially disposed spring-pressed article gripping fingers carried by said casing spaced above said lower fingers and normally disposed in a horizontal operative position, spring-pressed valve means above said upper fingers opening of said valves permitting fluid under pressure from the exterior of said casing to flow inwardly to force a tool to be retrieved upwardly into the interior of the casing to cause said tool to be moved into position to be engaged by said finger, a tubular valve operator slidably and rotatably disposed in said casing, said casing having a horizontally elongated opening therein formed with an upper locking portion and a lower locking portion extending oppositely from said upper locking portion, said opening being formed with an inclined cam surface extending between said locking portions, and a combined locking lug and cam member fixed to said operator and projecting into said opening, rotation of said operator in a counterclockwise direction relative to said casing, effecting simultaneous endwise downward movement of said operator to dispose said lug in said lower locking portion with said operator in a valve opening position said lug locking said valve operator and casing against endwise movement relative to each other in either valve opening or valve closing position.
